(57) **CLAIM**

I claim the ornamental design for a remote control for personal massager, as shown and described.

DESCRIPTION

FIG. 1 is a first perspective view of a remote control for personal massager.

FIG. 2 is a second perspective view of the remote control for personal massager.

FIG. 3 is a top view of the remote control for personal massager.

FIG. 4 is a bottom view of the remote control for personal massager.

FIG. 5 is a front view of the remote control for personal massager.

FIG. 6 is a rear view of the remote control for personal massager; and,

FIGS. 7 and 8 are left and right side views, respectively, of the remote control for personal massager.

The broken lines are directed to environment and are for illustrative purposes only; the broken lines form no part of the claimed design.
